UNITED STATES PATENT OFFICE

114,382

DESIGN FOR A COMBINATION CALENDAR DESK UNIT

William H. Kemp, Westfield, N. J.

Application January 24, 1939, Serial No. 82,551

Term of patent 7 years

To all whom it may concern:

Be it known that I, William H. Kemp, a citizen of the United States, residing in Westfield, Union County, New Jersey, have invented a new, original, and ornamental Design for A Combination Calendar Desk Unit, of which the following is a specification, reference being had to the accompanying drawing, forming a part thereof, in which:

Fig. 1 is a perspective view of a combination calendar desk unit showing my new design; and

Fig. 2 is a rear elevation of the same.

This application is a continuation-in-part of my copending application Serial No. D-76,196 filed March 30, 1938.

I claim:

The ornamental design for a combination calendar desk unit, as shown and described.

WILLIAM H. KEMP.
